UNITED STATES PATENT OFFICE.

THOMAS ALEXANDER MORRIS, OF LLANELLY, WALES.

TRUCK OR STAND FOR USE IN ANNEALING-FURNACES.

1,234,789.

Specification of Letters Patent.

Patented July 31, 1917.

Application filed October 31, 1916. Serial No. 128,719.

To all whom it may concern:

Be it known that I, THOMAS ALEXANDER MORRIS, a subject of the King of Great Britain and Ireland, residing at Llanelli, 5 in the county of Carmarthen, South Wales, have invented certain new and useful Improvements in Trucks or Stands for Use in Annealing-Furnaces, of which the following is a specification.

10 The invention relates to trucks or stands which are used in an annealing furnace to carry the plates or other articles through or into and out of the said furnace.

The objects of the present invention are 15 to construct a truck or stand which will increase the life of annealing pots or covers, which will always provide a dead flat annealing surface, which will provide a perfectly air-tight compartment which will 20 evenly distribute the heat, and which will accommodate annealing pots or covers of different sizes, for instance, one large pot or two smaller ones.

The invention is illustrated in Figures 1, 2 25 and 3 of the accompanying drawings as applied to a truck or bogie such as is used in a continuous annealing furnace, in which the truck passes through the furnace.

Fig. 1 is a vertical longitudinal section 30 of a truck or bogie on the line 1—1 of Fig. 3, and Fig. 2 is a horizontal section on the line 2—2 of Fig. 3; Fig. 3 is a transverse vertical section on the lines 3—3 of Figs. 1 and 2.

35 Fig. 4 is a transverse section through an annealing pot and rolling support for the articles to be annealed, showing how the invention may be applied to a stand to be used in a non-continuous annealing furnace.

40 In carrying the invention into effect as shown in Figs. 1, 2 and 3, I employ the body or lower part of an ordinary truck or bogie, having a flat horizontal surface *a* and vertical edges *b*. Within the edges *b* 45 I closely arrange a series of bricks *g* thus producing an upper horizontal surface *a'*. I build or fix an edging or rim of hard fire-bricks or of cast iron or other suitable material within and parallel to the vertical edges *b* of the said horizontal surface *a*. This edging may consist of a single line of 50 bricks *c*, or blocks of cast iron or other suitable material. Within this edging or rim *c*, and at a suitable distance therefrom, are placed a number of bricks or other separate supports *d*, which rest upon the upper hori-

zontal surface *a'* of the truck and serve as supports for cast iron plates *e*, upon which are placed the sheets or other articles to be annealed. The cast iron plates *e* have an 60 upper horizontal surface *e'*, which is preferably slightly higher than the upper surface of the said edging or rim *c*, as shown.

The supports *d* may vary in number and position according to requirements, but 65 should not impede the free play of the heat beneath the plates *e*.

The cast iron plates *e* are of such dimensions as to leave a space *e*² between them and the edging or rim *c*, into which space fits 70 the annealing cover or pot *f*. The cast iron plates *e* are likewise of such dimensions as to prevent the longer sides of the pot *f* from closing in to any considerable extent.

The supports *d* may also be arranged to 75 prevent the sides and ends of the pot *f* closing in. As shown some of the supports *d* are almost in contact with each other longitudinally, and others are almost in contact transversely; consequently they afford a 80 support to the pot *f* in both directions should the sides begin to close in.

The surface supporting the sheets or other articles to be annealed, being made in separate plates *e*, can be readily made to accommodate annealing covers or pots of different sizes, according to the sizes of the sheets to be annealed. One plate *e* may be removed, or it may be replaced by a smaller plate. Further, being made in separate plates or 85 sections, there is little or no warping, thus insuring flat sheets after annealing and preventing "red edges" being caused by air entering the cover or pot while cooling.

The cast iron plates *e*, by preventing the 90 longer sides of the pot *f* from closing in, keep the pot in shape and thus materially increase its life.

In the drawings the flat horizontal surface *a'* is produced by closely arranging 100 bricks *g*, as is usual, upon the body of the truck, such bricks being placed on their long edges.

The edging or rim *c* is produced by closely arranging other bricks or blocks upon their 105 ends so that parts thereof stand up above the surface *a'*.

Sand *h* is placed as usual around the pot *f*, to keep the pot air-tight.

i, *i*, are the usual channels containing 110 sand *j* to make an air-tight joint with part of the furnace, not shown.

In non-continuous annealing furnaces it is customary to employ an annealing stand or dish provided with an edging or rim and having grooves on its under side to receive 5 balls or spherical rollers running in channels. When applying the invention to a stand for use in a non-continuous furnace, I employ a supporting surface as shown in Fig. 4, which is not exactly like the old 10 dish but has a horizontal upper surface A and a rim or edging b. The horizontal surface A has on its under side the usual grooves A' and balls A². Upon the surface A I closely arrange bricks g similar to those 15 marked g in Figs. 1, 2 and 3, of the drawings, and I otherwise carry the invention into effect exactly as described with respect to Figs. 1, 2, 3, similar parts being marked with similar letters of reference in all the 20 figures.

What I claim as my invention is:—

1. An improved support for use in annealing furnaces, having a flat surface and edges, an upper horizontal surface within 25 said edges, a rim standing up above said upper horizontal surface, separate supports on said upper horizontal surface allowing a free distribution of heat, and separate metal plates on said supports of such dimensions 30 as to leave a space between them and the said rim to receive the annealing pot, substantially as set forth.

2. An improved support for use in annealing furnaces, having bricks closely arranged on their long edges to produce an upper flat 35 surface, other bricks closely arranged on their ends to produce a rim standing up above the said flat surface, a third series of bricks standing on said flat surface and acting as supports, and separate metal plates 40 on said supports of such dimensions as to leave a space between them and the said rim to receive the annealing pot, substantially as set forth.

3. An improved support for use in annealing furnaces, having a flat upper surface, vertical edges around said flat upper surface, bricks closely arranged on their long edges within the said vertical edges, other bricks closely arranged on their ends to produce a rim parallel to the said vertical edges and standing up above the first mentioned 45 bricks, a third series of bricks standing on the first mentioned bricks acting as supports and so disposed as to allow free circulation 50 of the heat between them, and separate metal plates standing on the said supports of such dimensions as to leave a space between the plates and the said rim to receive the annealing pot, substantially as set forth.

In witness whereof I have hereunto set my hand.

THOS. ALEXANDER MORRIS.
